FOREIGN PATENT DOCUMENTS

CA 2490955 6/2005

Primary Examiner — T. Chase Nelson*Assistant Examiner* — Ania Aman(74) *Attorney, Agent, or Firm* — Cohen & Grigsby, P.C.(57) **CLAIM**

The ornamental design for a grooved magnet, as shown and described.

DESCRIPTION

FIG. 1 is a perspective view of the grooved magnet embodying my new design as claimed herein.

FIG. 2 is a side view of the grooved magnet shown in FIG. 1.

FIG. 3 is a top view of the grooved magnet shown in FIG. 1.

FIG. 4 is a bottom view of the grooved magnet shown in FIG. 1.

FIG. 5 is a perspective view of an alternate embodiment of the grooved magnet shown in FIG. 1.

FIG. 6 is a side view of the grooved magnet shown in FIG. 5.

FIG. 7 is a top view of the grooved magnet shown in FIG. 5; and,

FIG. 8 is a bottom view of the grooved magnet shown in FIG. 5.
